(57) **CLAIM**

The ornamental design for a top for a water bottle, as shown.

DESCRIPTION

FIG. 1 is a perspective view of a top for a water bottle of the present invention;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines showing environmental structure are for illustrative purposes only and form no part of the claimed design.
